Fig. 2.

Des. 201,564

PAGE 3

Fig. 3.

Fig. 4

FIG. 1 is a front elevational view of a lawnsweeper embodying my new design the rear of the debris receptacle being flat and plain as indicated in FIGURES 2 and 3.

FIG. 2 is an elevational view taken from one side thereof.

FIG. 3 is an elevational view taken from the side opposite that shown in FIG. 2.

FIG. 4 is a top plan view of the sweeper.

The dominant features of the design reside in the portion shown in full line.

I claim:

The ornamental design for a lawnsweeper or the like, as shown and described.
